(57) **CLAIM**

The ornamental design for a triple-layer shoe insole, substantially as shown and described.

DESCRIPTION

FIG. 1 is a top side perspective view of a triple-layer shoe insole, showing my new design;

FIG. 2 is a detached status perspective view thereof;

FIG. 3 is a bottom view thereof;

FIG. 4 is a top view thereof;

FIG. 5 is a back view thereof;

FIG. 6 is a front view thereof;

FIG. 7 is a left view thereof; and

FIG. 8 is a right view thereof.

FIG. 9 is an enlarged view of portion 9 in FIG. 2;

FIG. 10 is an enlarged view of FIG. 7; and,

FIG. 11 is an enlarged view of FIG. 8.

The dash-dot-dash broken line rectangle frames define the cut lines of an enlarged view and form no part of the claimed design.

1 Claim, 11 Drawing Sheets
